UNITED STATES PATENT OFFICE.

JOSEPH BABST, OF HOBOKEN, NEW JERSEY, ASSIGNOR TO WILLIAM SCHIMPER & COMPANY, OF HOBOKEN, NEW JERSEY, A CORPORATION OF NEW JERSEY.

DESIGN FOR A HOLDER FOR POCKET-BOOKS.

No. 40,175.

Specification for Design.

Patented July 27, 1909.

Application filed May 29, 1909. Serial No. 499,254. Term of patent 3½ years.

To all whom it may concern:

Be it known that I, JOSEPH BABST, a subject of the Emperor of Germany, and resident of Hoboken, in the county of Hudson and State of New Jersey, have invented a new, original, and ornamental Design for a Holder for Pocket-Books, of which the following is a specification, reference being had to the accompanying drawings, forming part thereof.

The figure is a view in perspective of a holder for pocketbooks, showing my new design.

I claim:

The ornamental design for a holder for pocket-books, as shown.

JOSEPH BABST.
